UNITED STATES PATENT OFFICE.

EUGENE S. CRULL, OF SEDALIA, MISSOURI.

SHEATHING-LATH.

No. 838,357.

Specification of Letters Patent.

Patented Dec. 11, 1906.

Application filed September 26, 1905. Serial No. 280,163.

To all whom it may concern:

Be it known that I, EUGENE S. CRULL, a citizen of the United States, and a resident of Sedalia, in the county of Pettis and State of Missouri, have invented a new and useful Improvement in Sheathing-Laths, of which the following is a full, clear, and exact description.

The purpose of the invention is to provide a combination of sheathing and laths for plaster and stucco work on walls or ceilings, so constructed as to offer the least possible obstruction to the plaster-keys and a maximum of bearing or locking surface, and, furthermore, to so construct the article that each lath is capable of being almost completely surrounded by plastic material.

Another purpose of the invention is to provide a construction of sheathing and laths wherein the two factors are integral parts and which may be economically and readily produced and wherein the laths will be equally spaced from each other and from the sheathing, enabling much more smooth and regular work to be accomplished than ordinarily and with the expenditure of much less material.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of a corner portion of an apartment, showing sundry of the combined sheathing and lath laid to form the side walls and ceiling. Fig. 2 is an inner face view of a piece of sheathing and combined lath. Fig. 3 is a transverse section taken substantially on the line 3-3 of Fig. 2, and Fig. 4 is a longitudinal section taken practically on the line 4-4 of Fig. 3.

In the construction of the article the laths and the sheathing are made from one piece of material of suitable size, and A represents the sheathing, and B the laths, which are at the inner face of the sheathing, extending in parallel lines at an equal distance apart from end to end of the piece of material from which the article is made.

The upper edge 10 of the combined sheathing and laths is inclined from the back of the sheathing upwardly, as is shown in Fig. 3, and a corresponding inclination 11 is given to

the lower longitudinal edge of the said article, as is also shown in Fig. 3. In producing the laths B saw-kerfs 12 are carried from end to end of the material at its inner face, the said kerfs being at equal distances apart and of uniform width, and in producing the said kerfs the uppermost one is so placed as to have a lath B at the upper edge of the material and to have a kerf 13 at the lower edge of the material, so that when two of the articles are made to abut the upper lath B of the lower article will be spaced an equal distance from the lower lath of the upper article, as is the spacing between the intermediate laths, so as to provide a perfectly uniform keying-surface when the combined laths and sheathing are placed in position on a building.

The laths B are separated from the sheathing A throughout the entire length of the piece by means of a winding or circuitous rib C, forming an integral portion of the laths and sheathings at regular intervals, and in producing this rib vertical or transverse saw-kerfs are introduced of given lengths, of which 16 is a complete kerf and 14 and 15 portions of corresponding kerfs at opposite edges of the piece. The saw is introduced at one edge to produce the kerf 16 and at the opposite edge to produce the duplicate kerfs, so that, preferably, the said rib or bearing C assumes a circuitous formation, (shown in Fig. 4,) comprising longitudinal members 17, 17^a, and 19, adjacent to the edge of the material, and diagonal members 18 and 18^a, which incline in the opposite direction; but it will be understood that the lath may be of any desired length and that the rib C will appear as a series of diagonal members connected by longitudinal members parallel with opposite side edges of the article. The kerfs may be produced in any convenient manner.

It will be observed that by means of this construction the laths are integral with the sheathing, yet are separate therefrom for the major portion of their lengths, and that the laths are a uniform distance from the sheathing as well as a uniform distance from each other. It will be further observed that the connected and yet largely independent individuality of each lath B is provided for by the blind and hidden bearing or connecting ribs C, which are more frequent yet have less liability to obstruct plaster-keys than when ordinary laths are employed, wherein the parts corresponding to the said bearings

are the uprights to which the laths are attached. Each lath is capable of being practically surrounded on all sides by plastic material, and the laths being produced upon the 5 sheathing A in the manner shown and described are mechanically and accurately divided one from the other and from the sheathing or backing, all spacing being uniform and consistent with the best requirements.

10 The uniform and regular spacing between the laths and the sheathing effect a considerable saving in material, since the plaster in ordinary work is often forced between and back of the laths to such an extent as to 15 fall down and be of no service. Again, when the improved device is employed great solidity is given to the wall by reason of the strong, close, and compact combination of the 20 two thicknesses of wood alternating with the plaster, presenting an even plastic surface when the wall is completed, together with a strong combination of heat and cold resistance.

The winding or circuitous position of the 25 bearings or ribs C binding the laths and sheathings constitutes a continuous rail-support when the article is laid at every part in the length of each article, and therefore the article is adaptable to any studding 30 or joists however spaced. The beveled edges 10 and 11 when abutting sections are brought together constitute a more effective lock than nails or tongues or grooves, although the latter may be used if found desirable.

I desire it to be understood that any desired number of laths may be formed integral with a piece of sheathing and that the longitudinal kerfs 12 may be made intermittent 40 instead of continuous, as shown, without departing from the spirit of the invention.

In Fig. 1 I have illustrated the application of the improved lathing article to a structure in which D represents the ceiling lathing and sheathing, E the siding lathing and sheathing, and F the supports to which the sheathing is secured.

Having thus described my invention, I claim as new and desire to secure by Letters 50 Patent—

1. As an improved article of manufacture, a sheathing and laths integral with the

sheathing, separated therefrom a predetermined distance in their length, and separated from each other.

2. As an improved article of manufacture, a sheathing and laths formed integral with a face of the sheathing, separated from the sheathing at intervals in their length and separated from each other, one of the laths 60 extending to a longitudinal edge of the sheathing, another lath being spaced from the opposing longitudinal edge, both edges of the sheathing and the laths where they join the edges being upwardly and inwardly 65 inclined from the back of the sheathing.

3. As an improved article of manufacture, a sheathing, laths formed integral with the sheathing, separated from the sheathing at intervals in their length and separated from 70 each other, the distance between the laths and the sheathing being uniform and likewise the distance between the laths.

4. As an improved article of manufacture, a sheathing, a circuitous rib or bearing integral with the said sheathing, and laths integral with the said rib, the laths being spaced 75 from the said sheathing and from each other.

5. As an improved article of manufacture, a sheathing having an integral rib at one face, 80 consisting of opposing diagonal sections inclined in direction of each other and extending from one longitudinal edge of the sheathing to the other and bridge-sections connecting the diagonal sections and alternately 85 located at opposite longitudinal edges of the sheathing parallel therewith, and laths integral with said rib, which laths are spaced from each other and spaced from the sheathing.

6. As an improved article of manufacture, a sheathing provided on one face with a rib having longitudinal members connected by diagonal members, the longitudinal members being adjacent to the edges of the sheathing, 95 and laths secured to the rib and spaced from each other.

In testimony whereof I have signed my name to this specification in the presence of two subscribing witnesses.

EUGENE S. CRULL.
